United States Patent Office.

S. THOMPSON BARTON AND JOHN W. AFFRON, OF NEW ORLEANS,
LOUISIANA.

Letters Patent No. 101,212, dated March 29, 1870; antedated March 21, 1870.

IMPROVEMENT IN HASPS FOR TRUNKS, &c.

The Schedule referred to in these Letters Patent and making part of the same

To all whom it may concern:

Be it known that we, S. THOMPSON BARTON and JOHN W. AFFRON, of New Orleans, in the parish of Orleans and State of Louisiana, have invented a new and useful Improvement in Safety-Seal Fastenings for Trunks and other similar articles; and we do hereby declare that the following is a full, clear, and exact description thereof, which will enable others skilled in the art to make and use the same, reference being had to the accompanying drawings forming part of this specification, in which—

Figure 1 represents a side elevation of a portion of a trunk provided with my improved fastening.

Figure 2 represents a central cross-section of the same; and

Figures 3 and 4 represent detached portions thereof.

Similar letters of reference indicate like parts.

This invention relates to improvements in safety-fastenings for trunks, doors, and for other similar purposes, whereby it is designed to provide a simple, cheap, and secure fastening for the same.

It consists in a turn-button on a plate to which the hasp is to be fastened, provided with a hole through which a spring bolt may be passed after the button has been turned to the right position for holding the hasp, and a bracket on the said plate, through which the end of the said bolt may also be passed, to prevent the button being turned, as will be more fully described on reference to the accompanying drawings, wherein—

A represents a plate, which in this instance is se-

cured to the body of a trunk, and is provided with a button, B, and a fixed lug, C.

The button is provided with a hole, d, for the bolt D, and the holes b for a tape or wire to be sealed.

The bracket C is also provided with a hole for the end of the bolt.

The bolt D is provided with a bracket, a, which is also perforated with holes coinciding with the holes b in the button B.

E represents a hasp secured to the cover of the trunk, and provided with a slot for the reception of the button-head in the usual manner.

When the hasp has been slipped over the button, and the latter turned to the position shown in figs. 1 and 2, the bolt D is slipped through the hole d and the lower end inserted in the hole in the lug C, whereby the button is prevented from being turned.

A looped strip of sheet metal, F, may then be inserted in the holes b through the button and the bracket of the bolt, and the ends secured by a metallic seal, as shown in fig. 2.

Having thus described our invention,

We claim as new and desire to secure by Letters Patent—

The combination with the plate A of the button B and bracket C of the plate A, and the bolt D, substantially as and for the purpose described.

S. THOMPSON BARTON.
JOHN W. AFFRON.
